[57] CLAIM

The ornamental design for a lipstick case, as shown and described.

DESCRIPTION

FIG. 1 is a perspective view of a lipstick case showing my new design;

FIG. 2 is a front elevational view thereof, the rear elevational view, left side elevational view and right side elevational view appearing the same;

FIG. 3 is a top plan view thereof;

FIG. 4 is a bottom plan view thereof; and,

FIG. 5 is a perspective view shown in an open position. The broken line showing of lipstick in FIG. 5 is for illustrative purposes only and forms no part of the claimed design.

FIG.1

FIG. 3

FIG. 4

FIG. 2

FIG.5
